United States Patent Office

Des. 214,972

Patented Aug. 12, 1969

214,972

INHALER

Dean Richard Katerndahl, Wheaton, Ill., assignor to
Abbott Laboratories, North Chicago, Ill., a corporation of Illinois

Filed Sept. 19, 1968, Ser. No. 13,619

Term of patent 14 years

Int. Cl. D24—99

U.S. Cl. D83—1

FIG.1

FIG.2

FIG.3

FIG.4

FIGURE 1 is a perspective view of an inhaler showing my new design;

FIGURE 2 is a rear elevational view thereof, as viewed along the line 2—2 of FIGURE 1;

FIGURE 3 is a front elevational view thereof;

FIGURE 4 is a side elevational view thereof.

The dominant features of my design reside in the portions shown in full lines.

I claim:

The ornamental design for an inhaler, substantially as shown and described.
